UNITED STATES PATENT OFFICE.

ANTON RIEPPEL, OF NUREMBERG, GERMANY, ASSIGNOR TO MASCHINENBAU-
ACTIEN-GESELLSCHAFT NÜRNBERG, OF SAME PLACE.

GIRDER STRUCTURE FOR SUSPENSION-RAILWAYS.

SPECIFICATION forming part of Letters Patent No. 629,273, dated July 18, 1899.

Application filed December 30, 1896. Serial No. 617,493. (No model.)

To all whom it may concern:

Be it known that I, ANTON RIEPPEL, a subject of the King of Bavaria, and a resident of Nuremberg, Bavaria, German Empire, have 5 invented certain new and useful Improvements in Girder Structures for Suspension-Railways, of which the following is a specification.

The invention has been patented in England, No. 25,722, dated November 16, 1896; and in Germany, No. 91,642, dated May 8, 1896.

My invention relates to girder structures for suspension-railways; and it is the object to provide a light structure capable of resisting the one-sided torsion action when the track is traveled over and one adapted to follow the course described by the track and to provide sufficient room for the free lateral swinging of the carriage.

20 The invention relates to the details of construction, as will be hereinafter described, and particularly pointed out in the claims.

The invention is illustrated in the accompanying drawings, in which—

25 Figure 1 is a perspective view of the structure generally. Fig. 2 is a diagrammatic plan view of the upper horizontal girder. Fig. 3 is a similar view of the lower horizontal girder as used in curves; Figs. 4 and 5, plan views

30 of the upper and lower horizontal girders, respectively. Fig. 6 is a side elevation of the vertical and horizontal girders with the trestle in cross-section. Fig. 7 is a cross-section of the whole structure. Fig. 8 is a detail sec-

35 tional view on the line 6 6 of Fig. 6. Figs. 9, 10, and 11 are perspective and diagrammatic views of a modified form of construction. Figs. 12 to 15 are details of said modi-

40 fication, in which Fig. 12 is a side elevation of the vertical girder *a*, with the lower girder *c* in position, but the upper girder *b* only in-

dicated by a dotted line for clearness in order to show the omission of the middle beam. Fig. 13 is a plan view of the upper girder *b*;

45 Fig. 14, a cross-section on the line *s t* of Fig. 13, and Fig. 15 a cross-section on the line *q r* of Fig. 13.

This improved girder structure, in contradistinction to all the forms of construction 50 hitherto employed for similar purposes, consists of only one vertically-disposed truss

girder, which is stiffened at the top and bottom by two horizontally-disposed latticed or truss girders.

The upper horizontal girder *b*, which, as 55 shown in Figs. 2 and 4, consists of two side beams *b' b²* and a central beam *a'*, all trussed together by diagonal braces *b³* and transverse ties *b⁴*, is riveted by ordinary joints *k* to the top of the vertically-disposed girder *a*, Figs. 60 4 and 6, while the lower horizontal girder *c*, which, as shown in Figs. 3 and 5, consists of two side beams *c' c²* and a central beam *a²*, trussed together by diagonal braces *c³* and transverse ties *c⁴*, is similarly riveted by joints 65 *k'* to the bottom of the vertical girder *a*, Figs. 5 and 6. The middle beams *a'* and *a²* of the upper and lower horizontal girders *b* and *c* serve also as top and bottom beams for the vertical girder *a*. 70

The vertical girder *a* and the horizontal girder *b* are together supported at each end at the points *A* and *B* on the trestle-legs or oscillatory supports *S S'*, as shown in Fig. 1 in general perspective view and more in detail 75 in Fig. 6, a little play being allowed between the ends *a³* and *a⁴* of successive spans. The vertical loads and reactions resulting from the weight of the carriage and of the whole girder structure are thus received by the vertical girder *a* and transmitted to the supports *S S'* at the points *A* and *B*, which points also receive the horizontal reactions of the horizontal girder *b*. The lower horizontal girder *c*, which is connected, as before stated, to the 80 vertical girder *a*, is further connected at each end *C D* to the supports *S S'* by a truss formed of oblique tension-rods *l*, Figs. 1 and 5, arranged to transmit to said supports the horizontal reactions of the said girder *c*, the 85 points *C D* being vertically below the points *A* and *B*. 90

The side beams *c' c²* of the girder *c* are formed as rail-carriers, as shown in Fig. 7, and are further tied to each upper joint of 95 the vertical girder *a* by means of oblique tension-rods *f f'*, Figs. 1, 5, 14, and 15.

This improved girder structure has special advantages in that ample room is afforded for the free oscillation of the carriage (see 100 Fig. 7) and that the structure is suitable for use in curves of any desired curvature,

As shown in Figs. 2 and 3, the making of curved pieces is extremely simple, for the reason that only the lower horizontal girder c need be curved concentrically to the track, while the vertical girder a and also the upper girder b may remain straight. The preparation and also the fitting up of the girder structure is not, therefore, complicated or rendered more difficult by the existence of curved pieces. This improved arrangement affords, moreover, a means of making the ordinary superstructure more advantageous than where constructions necessitating the ordinary two or more vertical girders are employed.

As is well known, in view of the alterations of length produced by variations of temperature, it is advisable to place the superstructures of lengthy street-railway viaducts on oscillatory supports arranged at right angles to the axis of the track, because these can be of considerably lighter construction than fixed tie-beams. In straight stretches of track any desired number of vertical girders a alongside of one another may be connected by fixed links with the upper ends of the oscillatory supports S S' without impeding the free mobility of the latter, which may thus oscillate into positions parallel to themselves. On the other hand, in the case of curves in the track, the upper ends of the oscillatory supports S S' being arranged radially to the curve of the track will have their free mobility impeded when connected by more than one vertical girder a and will not, therefore, have the desired action under variations of temperature. By the use of only one vertical girder a , however, in accordance with the present invention, which girder is mounted or supported, as hereinbefore described, at the points A C and B D , the free mobility of the oscillatory supports S S' , even in curves, is in no way affected if only the ends a^3 a^4 of the girders, as shown in Fig. 6, be movable within certain limits on their supports.

Seeing that in street-railways constructed on the suspension-rail system the use of oscillatory supports is from economic and also (owing to their light appearance) from esthetic reasons particularly desirable, this improved form of girder structure shows a very considerable technical advance.

In cases in which it is a question of diminishing as far as possible the weight and obtaining a particularly light pleasing appearance the girder structure hereinbefore described may be carried out in the manner shown in the accompanying drawings, Figs. 9 to 15, without affecting its firmness and stability. The middle beams a' a^2 of the upper and under horizontal girders b c , which in the form of construction shown in Figs. 1 to 8 formed the top and the bottom beams of the

vertical girder a , as before described, in this modified form are omitted and the strains which would have been absorbed by the above-mentioned central beams a' a^2 are conveyed by the diagonals b^3 and c^3 of the upper and under horizontal girders b and c to the side beams b' b^2 and c' c^2 of the said upper and under girders. For this purpose, as shown in Figs. 12 to 15, the vertical girder a , consisting of the diagonal braces a^1 and vertical ties a^0 , is riveted to the joints k of the diagonals b^3 of the upper girder b and to the joints k' of the under girder c . A separate plan of the girder c , without the middle beam a^2 , is shown, diagrammatically, in Fig. 10, and reference may be had to Fig. 5 in other respects for details of construction, the middle beam being disregarded. The diagonals b^3 and c^3 therefore transfer all the strain and pressure which would have been absorbed by the central beams a' a^2 to the joints i i' of the side beams b' b^2 and the corresponding joints of the respective horizontal girders c' and c^2 .

Having now particularly described and ascertained the nature of the said invention and in what manner the same is to be performed, what I claim is—

1. A girder structure for suspension-railways comprising an upper horizontal truss-frame, a lower horizontal truss-frame adapted to have the track arranged along one edge thereof and the car suspended over said edge, a single vertical girder connected centrally to the upper and lower truss-frames, and a support for each end of the upper frames, substantially as described.

2. A girder structure for use in curves comprising a lower horizontal girder curved concentrically to the track, the end supports extending transversely of the track in a radial line adapted to have parallel oscillatory movement, the upper straight girder and the vertical girder connecting the lower curved girder and the upper straight girder also extending in a straight line, substantially as described.

3. In combination in a girder structure the oscillatory supports or trestle the vertical girder a and the horizontal girders b and c mounted on said supports the said horizontal girders each having at their opposite ends a single supporting-point whereby the said supporting-points A C , or B D , at one trestle always lie vertically under one another and admit of play whereby in curves the oscillation can take place unimpededly, substantially as described.

In witness whereof I have hereunto set my hand in presence of two witnesses.

ANTON RIEPPEL.
